UNITED STATES PATENT OFFICE.

ARCHIBALD McCORVIE, OF LUCKNOW, ONTARIO, CANADA.

TUG-CLIP.

SPECIFICATION forming part of Letters Patent No. 232,532, dated September 21, 1880.

Application filed January 26, 1880.

To all whom it may concern:

Be it known that I, ARCHIBALD McCORVIE, a citizen of Ontario, residing at Lucknow, in the county of Bruce and Province of Ontario, Canada, have invented certain new and useful Improvements in Tug-Clips; and I do hereby declare the following to be a full, clear, and exact description of the invention, such as will enable others skilled in the art to which it applies to make and use the same, reference being had to the accompanying drawings, and to letters and figures of reference marked thereon, which form a part of this specification.

This invention relates to an improved tug-clip for hames or horse-collars of that class in which the tug-strap is secured in a pintle-plate having a removable pintle; and it has for its object to provide for automatically securing the pintle in place. This object I attain by the means illustrated in the accompanying drawings, in which—

Figure 1 represents a front view of a horse-collar with my improvement attached thereto, and Fig. 2 a detached view of the removable pintle.

The letter A indicates a horse-collar of any description, and B the improved tug-clip, consisting of a pintle-plate, C, secured to said

collar and carrying a removable pintle, D, the said pintle being provided at its lower end with an annular recess, E, which is adapted to be engaged by a spring, G, secured to the collar so as to hold the pintle in place or permit it to be liberated in order to insert the end of the tug-strap. The collar is provided with the usual rings, H, through which the reins pass.

The operation of my improvement will be readily understood in connection with the above description without further explanation; and,

Having thus fully described my invention, what I claim, and desire to secure by Letters Patent, is—

A tug-clip consisting of a pintle-plate adapted to be secured to a horse-collar and a removable pintle provided with an annular recess at its lower end, and a spring connected to the collar and adapted to engage the recess in the pintle, substantially as specified.

In testimony whereof I affix my signature in presence of two witnesses.

ARCHIBALD McCORVIE.
